UNITED STATES PATENT OFFICE

2,334,169

DISK BRAKE

Ray G. Aurien, Chicago, Ill., assignor to American Steel Foundries, Chicago, Ill., a corporation of New Jersey

Application January 15, 1941, Serial No. 374,416

27 Claims. (Cl. 188—59)

My invention relates to a brake arrangement and more particularly to a novel disk type brake and actuating means supported between the wheels of a railway wheel and axle assembly.

My invention comprehends a disk brake arrangement supported inboard the wheels of a railway wheel and axle assembly wherein a rotor is driven by each wheel and stators are movable axially into frictional engagement with opposite faces of the associated rotor.

One object of my invention includes designing for such a disk brake novel actuating means wherein an upper and lower set of diagonally arranged interconnected levers are connected to the stators associated with each rotor and to respective power means supported on opposite sides of the wheel and axle assembly, said sets being operable to move the stators in opposite directions to clamp or squeeze the associated rotor therebetween.

Another object of my invention is to support the stators and actuating means between the wheels by a brake carrier mounted on journal means outboard the wheels.

A different object of my invention is to afford release means for returning the stators to their normal released positions, said means including pads of suitable resilient material supported on the brake carrier.

A further object of my invention is to design actuating means for such a disk brake wherein a live lever is connected to a piston of the brake cylinder, a dead lever is fulcrumed from said brake carrier, and said live and dead levers are connected to each other at corresponding ends and, intermediate their ends, to respective stators on opposite sides of a rotor.

A specific object of my invention is to design such a disk brake having a rotor and stators adjacent to each wheel actuated by sets of diagonally arranged levers connected to the stators above and below the axle at substantially diametrically opposite points, one lever of each set being fulcrumed to a brake carrier and another lever of said set being connected to power means mounted on said brake carrier midway said wheels, and a member connecting corresponding ends of said levers.

Other objects and advantages of my novel brake arrangement will be apparent from the following description and appended claims.

In the drawings, Figure 1 is a half top view of a railway car truck embodying my invention, part of the car truck being broken away adjacent to the wheel and axle assembly, and the

other half not being shown because it is similarly arranged.

Figure 2 is a sectional view of the structure shown in Figure 1, the section being taken substantially in the vertical planes indicated by lines 2—2 of Figure 1.

Figure 3 is an end view, half in section, taken from the right of Figure 1, the section being taken substantially in a transverse diagonally arranged plane indicated by line 3—3 of Figure 2.

Figure 4 is a fragmentary sectional view of the opposite end of the car truck shown in Figure 1, the section being taken in a horizontal transverse plane bisecting the axle.

Figure 5 is a fragmentary sectional view showing the manner of supporting each rotor, the section being taken substantially in a vertical plane indicated by the line 5—5 of Figure 3.

Figure 6 is a fragmentary sectional view of the release means for the stators, the section being taken substantially in a vertical transverse plane indicated by the line 6—6 of Figure 1.

Figure 7 is a fragmentary sectional view taken substantially in the longitudinal vertical plane indicated by the line 7—7 of Figure 3.

Figure 8 is a fragmentary sectional view of another modification of my invention, the section being taken substantially in the vertical transverse plane bisecting the wheel and axle assembly.

For the purpose of clarity, certain details are omitted from each figure where they are more clearly shown in other figures.

In detail, the railway car truck generally indicated at 2 comprises spaced side frames 4, 4 end rails 6, 6 and intermediate spaced transoms 8, 8 between which may be supported a bolster (not shown) in usual manner. The car truck is supported at each end by a wheel and axle assembly including a rotating axle 10 having journal ends accommodated within outboard journal boxes 12, 12 in customary manner. Each journal box 12 slidably engages as at 14, 14 the spaced pedestal jaws 16, 16 formed at each end of the side frame 4. On opposite sides of each journal box 12 are formed wing portions 18, 18 affording seats for the lower ends of coil springs 20, 20, and the upper ends of said springs may be seated against the top member of the side frame 4.

My novel braking means is disposed between the wheels 24, 24, which may be press-fitted on opposite ends of axle 10, and includes spaced

rotors 26, 26, each supported adjacent a wheel 24 by a driving member or tube 28 (Figure 3). Each tube 28 encircles the axle 10 in concentric relationship therewith and may be press-fitted as at 30 on an annular bearing portion formed on the inboard face of the hub 32 of each wheel. The outboard end of tube 28 may be afforded an outwardly flaring annular flange 34 seated against the inboard face of the plate of the wheel 36 as at 38 and secured thereto in any convenient manner.

Each rotor 26 is supported adjacent to the inboard end of the tube 28 in a manner best shown in Figure 5. It may be noted that each rotor 26 comprises arcuate segments 40, 40, each having a projecting lug 42 on its inner circumference received within a complementary opening 44 in the driving tube 28 for interlocking each segment 40 with said tube. A steel spring band 46 encircles each rotor 26 and is accommodated as at 48 within an annular channel formed on the outer circumference of said rotor. The adjacent ends of said band 46 may be welded as at 50 to securely retain the segments 40, 40 around the tube 28 and to maintain their alignment.

In frictional engagement with opposite faces of each rotor 26 as at 52 and 54 are wear plates 56 and 58 secured in any convenient manner to the respective inboard annular stator 60 and outboard annular stator 62. Each stator 60 and 62 encircles the axle 10 and may be formed in two sections in any convenient manner to facilitate assembly. On opposite sides of said stators 60 and 62 are formed horizontally outwardly extending arms 64, 64 and 66, 66 respectively, and the ends of said arms slidably engage as at 68, 68 (Figure 6) upper surfaces on the transverse channel members 70 and 71 disposed on opposite sides of the axle 10. The transverse members 70 and 71 project outboard the wheels 24, 24 and are secured at 72, 72 to the wing portions 18, 18 on the journal boxes 12, 12. As best shown in Figure 7 a lug 74 of bolt-like form projects outwardly from each wing portion 18 through an aligned opening in an end of the adjacent transverse member 70 or 71, and resilient bushings 76, 76 are sleeved over said lug to afford a resilient connection. A securing nut 78 is threaded on the end of each lug 74. It may be noted that the transverse members 70 and 71 form a brake carrier which is resiliently supported on the outboard journal boxes.

Power means for operating said stators are supported on each transverse member 70 and 71 at approximately the longitudinal center line of the car truck. Outwardly of the axle 10 a double-acting brake cylinder 80 is secured to a bracket 82 on the transverse member 70 and is afforded piston rods 84, 84 arranged to be actuated in opposite directions. Each piston rod 84 is pivotally connected as at 86 to the lower end of the diagonally arranged live lever 88 which is afforded a connection intermediate its ends as at 90 to a jaw-like lug 92 integrally formed on the inboard stator 60 above the axle 10. The upper end of said lever 88 is pivotally connected as at 94 to the inboard end of the link or lever connector 96, said link 96 extending over said rotor and stators for pivotal connection as at 98 at its outboard end with the upper end of the diagonally arranged dead lever 100. The dead lever 100 is pivotally connected as at 102 intermediate its ends to a bracket or lug 104 formed adjacent to the top of the outboard stator 62 above the axle. The lower end of said dead lever 100 is fulcrumed as at 106 to

75 a fulcrum bracket 108 on the transverse member 70.

In similar manner inwardly of the axle a brake cylinder 110 is supported on the bracket 112 secured on the transverse member 71 and is afforded oppositely directed piston rods 114, 114, each having a pivotal connection as at 116 to the upper end of a diagonally arranged live lever 118. Intermediate its ends the live lever 118 is pivotally connected as at 120 (Figure 4) to the jaw-like bracket or lug 122 formed on the inboard stator 60 beneath the axle 10 in substantially diametrically opposite relationship with the lug 92. The lower end of said live lever 118 may be pivotally connected as at 124 to the inboard end of the link or lever connector 126 which extends transversely beneath the rotor and stators and which is afforded at its outboard end a pivotal connection as at 128 to the lower end of the diagonal dead lever 130. Intermediate its ends the dead lever 130 is pivotally connected as at 132 to the jaw-like bracket 134 formed on the outboard stator 62 beneath the axle and substantially diametrically opposite to lug 104. The upper end of the dead lever 130 is pivotally connected as at 136 to the fulcrum bracket 138 secured to the transverse member 71.

The operation of the top and bottom sets of the diagonally arranged levers is readily apparent. Upon application of the power means the pistons of the respective brake cylinders 80 and 110 simultaneously move outboardly and the live levers 88, 88 and 118, 118 urge the inboard stators 60, 60 axially into engagement with the inboard faces of the rotors 26, 26. Continued application rotates the outboard dead levers 100, 100 and 130, 130 in an inboard direction to axially move the outboard stators 62, 62 against the outboard faces of the rotors.

Release means for said stators (Figure 6) are afforded by metal-faced annular resilient bushings 140, 140 over which the adjacent ends of the arms 64 and 66 respectively are sleeved as at 142, 142 and positioned as at 144, 144 by rings 146, 146 secured as by welding to the outer circumferential metal-facing on the resilient bushings 140, 140. A bolt 148 extends through said bushings and an upstanding circular lug 150 secured to the transverse member 70 between the ends 64 and 66 of said stators. It is apparent that as the stators move toward each other, the resilient bushings 140, 140 are placed in shear and as the power means are released the resilient bushings return the stators to their normal released positions.

The journal box 12 is held against tipping or rotation upon application of the power means by inboard and outboard torque arms 152, 152 secured to the top of each journal box 12 as at 154, 154 and secured at their opposite ends to the side frame 4 as at 156, 156.

In the modification shown in Figure 8, the braking means are substantially identical with those previously described and differ therefrom in the manner of connection of the rotor 160 to the normally rotating outer axle or housing 152 of a well-known roller bearing wheel and axle assembly. The outer axle 162 is afforded adjacent to each wheel an annular flange 164 with spaced recesses 166, 166 to accommodate complementary lugs 168, 168 formed on the inner circumferential portions of the rotor 160. It is contemplated that the rotor 160 may be formed in segmental portions which may be retained and aligned in proper relationship by a steel spring

band 170 around its outer circumference in a manner similar to that previously described.

It is to be understood that I do not wish to be limited by the exact embodiments of the device shown which are merely by way of illustration and not limitation as various and other forms of the device will, of course, be apparent to those skilled in the art without departing from the spirit of the invention or the scope of the claims.

I claim:

1. In a vehicle, a frame, a supporting wheel and axle assembly comprising an axle with wheels thereon, frame supporting members on said assembly, a brake carrier on opposite sides of said assembly and supported from said members, braking means including a rotor driven by said assembly inboard each wheel, stators supported by said carrier on opposite sides of each rotor, power means on said carrier on opposite sides of said assembly, and sets of interconnected levers on opposite sides of said assembly operatively connected to the stators associated with each rotor, the sets on one side of said assembly being operatively connected to one of said power means and the sets on the other side of said assembly being operatively connected to the other of said power means.

2. In a brake arrangement, a wheel and axle assembly comprising an axle with wheels thereon, frame supporting members on said assembly, braking means inboard said wheels including rotatable brake elements driven by said assembly adjacent each wheel, nonrotatable brake elements supported by said members and arranged for engagement with opposite faces of the associated rotatable brake element, power means supported on opposite sides of said assembly and means operative to urge said elements into frictional engagement including upper sets of diagonally arranged levers operatively connected to said nonrotatable elements and one of said power means, and lower sets of diagonally arranged levers operatively connected to said nonrotatable elements and the other power means.

3. In a vehicle, a supporting wheel and axle assembly including a rotating axle with a wheel thereon, a frame supporting member on said axle outboard said wheel, a frame supported thereon, braking means inboard said wheel including rotors driven by said assembly, stators disposed on opposite sides of each rotor for frictional engagement therewith and supported by said frame supporting member, and actuating means inboard said wheel including sets of interconnected live and dead levers operatively connected to said stators at substantially diametrically opposite points.

4. In a vehicle, a supporting wheel and axle assembly including a rotating axle with a wheel thereon, a frame supporting member on said axle outboard said wheel, a frame supported thereon, braking means inboard said wheel including rotors driven by said assembly, stators disposed on opposite sides of each rotor for frictional engagement therewith and supported by said frame supporting member, and actuating means inboard said wheel including sets of interconnected live and dead levers operatively connected to said stators at substantially diametrically opposite points, and torque arms connected to said member and to said frame.

5. In a railway car truck, a truck frame, a supporting wheel and axle assembly comprising an axle with wheels thereon, journal means outboard said wheels, a brake carrier extending be-

tween said journal means and supported from opposite sides thereof, rotors driven by said wheels, stators and power means resiliently supported by said carrier, and actuating means for said stators including interconnected live and dead levers connected to said power means and said carrier respectively and connected intermediate their ends to respective stators.

6. In a railway car truck, a truck frame, a supporting wheel and axle assembly comprising an axle with wheels thereon, journal means outboard said wheels, a brake carrier supported from opposite sides of said journal means, braking means between said wheels including rotors driven by said wheels, stators and power means supported by said carrier, pairs of interconnected levers fulcrumed from said carrier and connected to said power means respectively for moving said stators into frictional engagement with said rotors, and torque members connecting said journal means and said frame.

7. In a vehicle, a frame, a supporting wheel and axle assembly comprising an axle with wheels thereon, frame supporting members on said assembly, a brake carrier on opposite sides of said assembly and resiliently supported from said members, braking means including a rotor driven by said assembly inboard each wheel, stators supported by said carrier on opposite sides of each rotor, power means on said carrier on opposite sides of said assembly, and sets of interconnected levers operatively connected to the stators associated with each rotor, each of said power means being operatively connected to certain of said sets of levers.

8. In a railway car truck, a truck frame, a supporting wheel and axle assembly comprising an axle with wheels thereon, journal means outboard said wheels, a brake carrier supported at opposite sides of said journal means, braking means between said wheels including rotors driven by said wheels, stators and power means supported by said carrier, and sets of levers for bringing said stators into engagement with respective rotors, each set including interconnected levers pivotally connected respectively to said carrier and to said power means and connected intermediate their ends to said stators.

9. In a railway car truck, a truck frame, a supporting wheel and axle assembly comprising an axle with wheels thereon, journal means outboard said wheels, a brake carrier extending between said journal means and supported from opposite sides thereof, braking means between said wheels including rotors driven by said wheels, stators and power means supported by said carrier, and interconnected live and dead diagonal levers operatively associated with said stators and said power means, and release means on said carrier for said stators.

10. In a railway car truck, a truck frame, a supporting axle with wheels thereon, braking means comprising a rotor supported by each wheel, stators disposed on opposite sides of said rotor and supported outwardly of said wheels, power means on opposite sides of said axle, and sets of interconnected diagonally arranged levers operatively connected to said stators and to said power means.

11. In a vehicle, a supporting axle with wheels thereon, journal means therefor, a rotor driving member encircling said axle and mounted on each wheel, a rotor supported on each member, transverse members mounted on said means, stators supported by said transverse members at

opposite sides of each rotor, power means supported between the wheels, and levers operatively connected to said power means and the stators associated with each rotor for moving said stators into frictional engagement therewith.

12. In a railway car truck, a truck frame, a supporting axle with wheels thereon, braking means comprising a rotor supported by each wheel, stators disposed on opposite sides of said rotor and supported outboard said wheels, power means between said wheels, and means for moving said stators into engagement with respective rotors including sets of interconnected diagonally arranged levers operatively connected to said stators and to said power means.

13. In a railway car truck, a truck frame, a supporting axle with wheels thereon, journal means outboard said wheels, a brake carrier supported at opposite sides of said journal means, braking means between said wheels including rotors driven by said wheels, stators and power means supported by said carrier, and sets of diagonally arranged levers operatively associated with said stators and power means, and resilient pads on said carrier for releasing said stators.

14. In a railway car truck, a supporting axle with wheels thereon, braking means between said wheels including spaced rotors each driven by the adjacent wheel, stators supported on opposite sides of each rotor, double-acting power means supported between said wheels at each side of said assembly, and diagonally arranged levers operatively connected to said stators and to said power means.

15. In a railway car truck, a truck frame, a supporting axle with wheels thereon, journal means for said axle, braking means comprising a rotor supported by each wheel, stators disposed on opposite sides of each rotor and supported by said journal means outwardly of said wheels, power means between said wheels, and sets of interconnected levers disposed above and below said axle and connected to respective stators and power means.

16. In a brake arrangement, a wheel and axle assembly comprising an axle and a wheel, a rotor driven by said assembly, stators adapted for engagement with said rotor, power means supported at opposite sides of said axle, and brake levers above and below the axle, said levers being connected to respective stators and operatively associated with respective power means.

17. In a railway car truck, a supporting axle with wheels thereon, braking means between said wheels including spaced rotors each supported from the adjacent wheel, stators supported on opposite sides of each rotor, and actuating means for the stators associated with each rotor including levers supported from opposite sides of said assembly and connected to each stator above and below said axle.

18. In a railway car truck, a supporting wheel and axle assembly comprising an axle with wheels thereon, braking means between said wheels including spaced rotors each supported from the adjacent wheel, stators supported on opposite sides of each rotor, power means supported on opposite sides of said assembly, and sets of levers operatively connected intermediate their ends to the stators associated with each rotor and each lever being fulcrumed at one end thereof and operatively connected at the opposite end thereof to the associated power means.

19. In a railway car truck, a supporting wheel

and axle assembly comprising an axle with wheels thereon, braking means between the associated wheels including spaced rotors each driven by the adjacent wheel, stators supported on opposite sides of each rotor, power means mounted on opposite sides of said assembly, and sets of diagonally arranged levers operatively connected to said stators and to said power means.

20. In a brake arrangement, a wheel and axle assembly comprising an axle with wheels thereon, a rotor driven by each wheel, stators supported at opposite sides of said rotor, pairs of levers at each end of said assembly and actuating means therefor, one of said pairs being positioned above and the other being positioned below said axle, and each of said pairs comprising a dead lever and a live lever connected at one end thereof to each other and at intermediate points to respective stators, said live lever being connected at its opposite end to certain of said actuating means, and said dead lever being connected at its opposite end to a fixed fulcrum.

21. In a brake arrangement, an axle with wheels thereon, rotors driven by said wheels, stators supported at opposite sides of said rotors, and actuating means for said stators, said means comprising spaced cylinders, live levers positioned above and below said axle, and dead levers positioned above and below said axle, each live lever being connected at one end thereof to an associated dead lever, at the opposite end thereof to one of said cylinders, and at an intermediate point to an associated stator, each of said dead levers being connected at one end thereof to an associated live lever, at the opposite end thereof to a fixed fulcrum, and at an intermediate point to an associated stator.

22. In a brake arrangement, an axle with wheels thereon, a rotor driven by each wheel, stators mounted at opposite sides of said rotor, levers extending above and below said axle and operating said stators, and actuating means for said levers, certain of said levers being connected at one end thereof to said actuating means, at the opposite end to an end of an associated lever, and at an intermediate point to an associated stator, said associated lever being connected at the opposite end thereof to a fixed fulcrum, and at an intermediate point to the adjacent stator.

23. In a brake arrangement, a wheel and axle assembly comprising an axle with wheels thereon, rotors driven by said wheels, stators supported at opposite sides of said rotors, and operating means comprising levers extending above and below said axle for engagement with respective stators, said levers being supported from opposite sides of said assembly.

24. In a brake arrangement, an axle with wheels thereon, journal means for said axle, rotors driven by said wheels, stators supported adjacent said rotors for frictional engagement therewith, actuating means for said stators, and release means for said stators comprising resilient pads associated therewith and adapted to be placed in shear upon actuation of said stators.

25. In a brake arrangement, a wheel and axle assembly comprising an axle and a wheel, a frame supported from said assembly, a rotor driven by said assembly, stators at opposite sides of said rotor for braking engagement therewith, brake levers, a connection between said levers at corresponding ends thereof, said levers being connected intermediate the ends thereof to respective stators, and a power cylinder mounted on

said frame, the opposite end of one of said levers being operatively connected to said cylinder and the opposite end of the other of said levers being pivotally fulcrumed from said frame, said levers and said connection being disposed wholly in a plane at one side of said axle.

26. In a brake arrangement, a wheel and axle assembly comprising an axle and a wheel, a frame supported from said assembly, a rotor driven by said assembly, stators at opposite sides of said rotor for braking engagement therewith, brake levers, a connection between said levers at corresponding ends thereof, said levers being connected intermediate the ends thereof to respective stators, and a power cylinder mounted on said frame, the opposite end of one of said levers being operatively connected to said cylinder and the opposite end of the other of said levers being pivotally fulcrumed from said frame, said levers and said connection being disposed wholly in a

plane at one side of said axle and extending thereabove.

27. In a brake arrangement, a wheel and axle assembly comprising an axle and a wheel, a frame supported from said assembly, a rotor driven by said assembly, stators at opposite sides of said rotor for braking engagement therewith, brake levers, a connection between said levers at corresponding ends thereof, said levers being connected intermediate the ends thereof to respective stators, and a power cylinder mounted on said frame, the opposite end of one of said levers being operatively connected to said cylinder and the opposite end of the other of said levers being pivotally fulcrumed from said frame, said levers and said connection being disposed wholly in a plane at one side of said axle and extending therebelow.

RAY G. AURIEN.
